[57] **CLAIM**

The ornamental design for a valve stabilizer bracket, as shown and described.

DESCRIPTION

FIG. 1 is a perspective view of a valve stabilizer bracket showing my new design;

FIG. 2 is a front elevational view;

FIG. 3 is a rear elevational view thereof;

FIG. 4 is a top plan view of the valve stabilizer bracket;

FIG. 5 is a bottom plan view thereof; and;

FIG. 6 is a side elevational view thereof, the side opposite view being a mirror image.

The broken line showing of the valve is for illustrative purposes only and forms no part of the claimed design.
